GOLF CLUB RAKE ATTACHMENT

Albert A. Salvatore, 109 Hibiscus Ave., Weymouth, Mass. 02188, and Joseph M. Fucci, 147 Lake St., East Weymouth, Mass. 02189

Filed Apr. 24, 1975, Ser. No. 571,362

Term of patent 14 years

Int. Cl. D8—05

U.S. Cl. D8—13

FIG. 4

FIG. 5

FIG. 6

FIG. 7

FIG. 1 is a front perspective view of a golf club rake attachment showing our new design;

FIG. 2 is a top plan view thereof;

FIG. 3 is a front view thereof;

FIG. 4 is a side view thereof with the side not shown being substantially a mirror image of this figure;

FIG. 5 is a rear view thereof;

FIG. 6 is a bottom plan view thereof; and

FIG. 7 is a side view thereof showing a prong portion of the rake in the folded position.

We claim:

The ornamental design for a golf club rake attachment, as shown and described.
